(57) **CLAIM**

The ornamental design for an assist grip for agricultural vehicle, substantially as shown and described.

DESCRIPTION

FIG. 1 is a perspective view of an assist grip for agricultural vehicle showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a rear view thereof; and,

FIG. 8 is a reduced perspective view thereof shown in use condition.

The broken line showing of a bottom portion of the assist grip for agricultural vehicle in FIGS. 1-5, and 7, and the broken line showing of the vehicle in FIG. 8 is included for the purpose of illustrating environmental structure and forms no part of the claimed design.

1 Claim, 8 Drawing Sheets
